UNITED STATES PATENT OFFICE

LOGAN L. MALLARD, OF NORFOLK, VIRGINIA

TRACTOR TOY

Application filed April 22, 1929. Serial No. 357,288.

This invention relates to new and useful improvements in toys and the primary object is to provide a toy designed in the form of a tractor which is adapted to be drawn along 5 the ground by a child through the medium of a flexible connection.

A further object of the invention resides in providing a device of the character mentioned in which opposed guide members are 10 provided between which operates loosely disposed ground engaging elements, the latter pushing one another forwardly as the device is drawn along the ground.

Still another object of the invention resides 15 in providing a frame comprising opposed substantially oval shaped guide members or tracks upon and between which the loosely disposed ground engaging members are supported, so that as the device is propelled, 20 these ground engaging elements will travel continuously around the opposed members, themselves forcing one another forwardly into ground engaging position.

Still another object resides in providing a 25 device which will be extremely novel in appearance, interesting to children as well as simple and durable in construction.

With these and numerous other objects in view my invention consists in the novel features of construction, combination and arrangement of parts as will be hereinafter referred to and more particularly pointed out in the specification and claims.

In the accompanying drawings forming a 35 part of this application

Figure 1 is a side elevation of a toy constructed in accordance with my invention;

Figure 2 is a vertical section therethrough as seen on the line 2—2 of Figure 1;

Figure 3 is a fragmentary plan view thereof with parts broken away;

Figure 4 is a vertical longitudinal section as seen on the line 4—4 of Figure 3;

Figure 5 is an end elevation of a slight 45 modified form of the invention and

Figure 6 is a vertical section through the latter as seen on the line 6—6 of Figure 5.

In describing the invention I shall refer to the drawings in which similar reference 50 characters designate corresponding parts

throughout the several views and in which 1 and 2 designate substantially oval-shaped track members which are positioned in opposed relation and held in spaced relation one to the other through the medium of bracing elements 5 and 6. These track members are formed preferably of metal and are substantially channel-shaped in cross section, as clearly shown in Figure 2 of the drawings. The purpose of this will be hereinafter and 55 more particularly set forth.

Supported on certain of the transverse bracing elements 5 is a member 7 representing a pilot house or cock-pit in which is disposed a figure represented by the numeral 8. Any 60 form of figure or member may be placed in this position as a substitute if desired, as this forms no essential feature of the invention.

The tractor feature of this device is supplied by the medium of a plurality of blocks 65 9, in the ends of which are provided grooves 10 for reception therein of the outer-most horizontal flange of the channel-shaped members 1 and 2, as clearly shown in Figures 2 and 4 of the drawings. These blocks 9 are 70 swung into place between the track members 1 and 2 so that the grooves 10 receive the upper-most flanges of these members 1 and 2 and said blocks slide loosely and readily over these members 1 and 2. As many of the 75 blocks may be provided as desired to fill the entire space, if desired, but preferably a less number is provided than would be necessary to fill the entire rack so that the blocks may drop downwardly by gravity over the curved 80 forward portion of the members 1 and 2 as the device is propelled forwardly.

These blocks 9 are not connected together but, as stated, merely loosely applied on the members 1 and 2. The outer faces of these 85 blocks are grooved longitudinally of the length thereof and have introduced therein strips 11 of any desired material such as rubber, felt or the like, so as to frictionally engage the ground as the device is propelled 90 thereover.

A bail member 12 is engaged with the members 1 and 2 at the forward end thereof to 95 which is connected a flexible connection 13 so that the device may be drawn over the 100

ground by a child playing therewith. As the device is drawn forwardly the elements 9 contacting with the surface of the ground will be forced rearwardly one against the other and said members are forced over the tracks 1 and 2, travelling continuously thereover. As the block members 9 on the upper stretch of the track members 1 and 2 reach the forward curvature of said members they will drop downwardly by gravity into position to be engaged with the surface of the ground. In this manner a tractor is provided wherein the tractor elements are themselves disconnected and force one another over the tracks and into ground engaging position.

In Figures 5 and 6 as shown a slightly modified form of ground engaging elements. Each such element, designated by the numeral 14 is made from a single strip of metal bent and looped to form a hollow member. One face of the member is corrugated as shown at 15, the corrugations extending longitudinally of the member to form friction means for engaging the surface of the ground. The end edges of the member 14 are recessed as shown at 16 to receive therein the upper horizontal flanges of the track members 1 and 2. This is one modification of down-engaging elements and it will be understood that various other modifications may be utilized. In the preferred form of the invention using the blocks 9 the weight of the blocks tend to retain the device against the surface of the ground. When using the modification as shown in Figures 5 and 6, should the device be too light, a weight member may be provided in connection with the figure or housing held between the opposed track members.

This toy, as stated hereabove, is useful for instruction purposes and to carry out this idea, the upper faces of the blocks 9 are preferably respectively provided with letters of the alphabet, which may be painted or otherwise inscribed thereon. As the device is propelled these letters may be viewed from the top of the device and as the blocks move forwardly on the device the various letters may be studied of a child playing with the toy. The use of letters is, of course, illustrated of one means of applying instruction or educational elements to this device and I do not wish to be limited strictly to the use of the letters of the alphabet as it is apparent that various other illustrations may be used to accomplish the same purpose.

From the foregoing description of the construction of my improved device, the operation thereof will be readily understood and it will be seen that I have provided a simple, inexpensive and efficient means for carrying out the objects of the invention.

While I have particularly described the elements best adapted to perform the func-

tions set forth, it is obvious that various changes in form, proportion and in the minor details of construction may be restored to, without departing from the spirit or sacrificing any of the principles of the invention.

Having thus described the invention what I claim is:

1. In a toy of the class described, a body member characterized by spaced endless track members, bracing elements connecting said track members, and a plurality of disconnected track-retained ground engaging members slidably mounted thereon, adapted to move over said tracks as the device is propelled.

2. In a toy of the class described, a body member characterized by spaced endless track members, bracing elements connecting said track members, and a plurality of disconnected track-retained ground engaging members slidably mounted thereon, adapted to move over said tracks as the device is propelled.

3. In a toy of the class described, a body member characterized by spaced endless track members, bracing elements connecting said track members, a plurality of disconnected track-retained ground engaging members slidably mounted thereon, adapted to move over said tracks as the device is propelled, and friction means on the ground engaging faces of said last mentioned members.

4. In a toy of the class described, a body member characterized by spaced endless track members, bracing elements connecting said track members, a plurality of members slidably engaged with and adapted to travel over said track members, said last mentioned members being disconnected and adapted to contact with the surface of the ground as the device is propelled and push one another endlessly around said track members.

5. In a toy of the class described, a body member characterized by spaced endless track members, bracing elements connecting said track members, a plurality of block-like members slidably engaged with said track members, said block-like members being disconnected and adapted to engage the surface of the ground when travelling over the lower stretch of the track members as the device is propelled, pushing one another endlessly over said track members, and friction means on the outer ground engaging surfaces of said block-like members.

6. In a toy of the class described, a body member characterized by spaced endless track members having inwardly extending flanges thereon bracing elements connecting said track members, a plurality of disconnected block-like members having grooves in the ends thereof receiving the flanges of the track members therein to permit loose slideable movement to said block-like members on

the track members, said block-like members being adapted to contact with the surface of the ground in movement over the lower stretch of the track members and push one another endlessly over the latter as the device is propelled.

7. In a toy of the class described, a body member characterized by spaced endless track members, bracing elements connecting said track members, and a plurality of disconnected track-retained ground engaging members slidably mounted thereon, said ground engaging members having instructional indicia on the outer faces thereof observable as said members travel over the upper stretch of said track members, said ground engaging members travelling over the lower stretch of said track members pushing one another endlessly over the track members as the device is propelled.

8. In a toy of the class described, a body member characterized by spaced endless track members, bracing elements connecting said track members, a plurality of disconnected track-retained ground engaging members slidably mounted thereon, said ground engaging members having instructional indicia on the outer faces thereof observable as said latter members travel over the upper stretch of said track members, friction means on said outer faces of the ground engaging members to assist in the movement of the latter over the lower stretch of the track members as the device is propelled, said ground engaging members on the lower stretch of the track members pushing one another and the remaining ground engaging members endlessly over said tracks, as and for the purposes described.

40 In testimony whereof I affix my signature.
LOGAN L. MALLARD.
